UNITED STATES PATENT OFFICE.

WALTER E. HITCHCOCK, OF BLANCHARD, IOWA.

CULVERT.

Application filed August 21, 1922. Serial No. 583,297.

To all whom it may concern:

Be it known that WALTER E. HITCHCOCK, a citizen of the United States, residing at Blanchard, in the county of Page and State of Iowa, has invented certain new and useful Improvements in Culverts, of which the following is a specification.

My invention relates to culverts and particularly to a head therefor designed for the purpose of supporting or retaining the bank at each end of the culvert.

The principal purpose of this invention is the provision of a sheet metal wing wall which may be readily attached to culverts of standard size and which will effectually prevent sliding of the earth adjacent the terminals of the culvert and also caving in of the earth surrounding the culvert by reason of the fact that water cannot flow around the culvert and carry away the soil.

A further object is to provide a head or wing wall which may be formed in sections and built either before application to the culvert terminal or at the time of application.

A further feature resides in the peculiar manner of attaching the wall to the culvert.

A further feature resides in a culvert wall which may be adapted for use with either circular or square culverts by simply forming the opening circular or rectangular as the case may require.

In the accompanying drawings forming a part of this specification,—

Figure 1 is an end view of one form of my culvert wall illustrating its application to a culvert, circular in cross section;

Figure 2 is a central vertical section through the wall shown in figure 1, the culvert being shown in side elevation;

Figure 3 is a side elevation of the wall at one end of a culvert;

Figure 4 is an end view of another form of my invention, illustrating its application to a culvert of rectangular cross-section;

Figure 5 is a side elevation of the arrangement shown in Figure 4.

Figure 6 is a horizontal sectional view on the line 6—6 of Figure 5, and

Figure 7 is a detail section of a modified form of attachment.

Referring now more specifically to the drawings by numerals of reference, 2 indicates a culvert of the ordinary type, in this instance being shown as of circular cross-section.

The wing-wall or head is indicated generally by the numeral 4, and comprises a relatively rigid sheet metal plate preferably rectangular, and while it may take the form of a single sheet, is preferably formed of a plurality of sections 6 whose meeting edges may overlap and be riveted together or may be joined by metal strips 8 secured to the respective sections in any suitable manner, such for example as by bolts 9.

The lateral edges of the plate 4 are turned rearwardly to provide earth retaining flanges 10, which incidently serve to reinforce the wing-wall and obviate buckling thereof.

Upon the upper horizontal edge of the plate, is mounted a crown plate 12 of triangular form, the upper walls of which slope oppositely from the apex of the crown toward the side edges of the main plate. The upper wall or edge of the crown plate is also provided with a rearwardly directed flange 14 which at their lower portions join or abut the upper ends of the flanges 10 of the plate 4 at the point *x* in figure 3.

The crown plate may also, if desired, be formed in sections joined by a metal strip 15, or by overlapping the adjacent edges and then riveting or spot welding. The crown plate 12 may be attached to the plate 4 by means of straps 16 secured by rivets 18.

In addition to its connection with the culvert 2, the plate 4 and crown 12 is supported principally by a plurality of metal posts or stakes 19 which are driven into the earth and secured to the inner face of the plate 4 and crown 12 by rivets 21 or the like.

For the purpose of attaching the wall to the rim of the culvert at its mouth, I provide a series of angle clips 22 secured respectively to the face of the plate 4 and to the inner wall of the culvert adjacent its opening by rivets 24. As an alternative form which will be found entirely practical, I may provide the plate 4 adjacent its opening with a series of integral tongues which may be bent inwardly and secured to the culvert in the manner described.

The form or arrangement shown in figure 4, except for the fact that the opening in the plate 4 is rectangular to accommodate a culvert of like character, is quite similar to the form shown in figure 1 and the foregoing description substantially covers said figure 4. However, in this figure 4, the plate 4 is attached to the culvert by integral tongues 25 arranged around the wall of the

rectangular opening and secured by rivets 26. In the present arrangement I have shown means for anchoring the wing-wall against movement tending to separate it from the culvert, this means comprising a rod or cable 30 attached at each side of the wall to the lateral flanges 10 near their upper ends or at a point intermediate the longitudinal center line of the culvert and the upper ends of the lateral posts or stakes, and at their lower ends in Fig. 3 to stakes 32 driven into the earth adjacent to the side of the culvert, or as shown in Fig. 5 to suitable fastening devices such as eyes 33 secured to the sides of the culvert. While these are preferred methods of bracing the wing wall 4, it is understood that other forms may be adopted within the scope of the attached claims.

20 In Fig. 7, I show a modification and it is a view similar to Fig. 6, with the exception that the culvert 2 is corrugated, and the tongues 25' are bent to conform to the curvature of the end corrugation, and secured by rivets 26.

From the foregoing description of the construction of my improved apparatus, it will be seen that I have provided a simple, inexpensive and efficient means for carrying out the objects of the invention, and while I have particularly described the elements best adapted to perform the functions set

forth, it is obvious that various changes in form, proportion and in the minor details of construction may be resorted to without departing from the spirit or sacrificing any of the principles of the invention.

Having thus described my invention, what I claim as new and desire to protect is:

1. In a device of the character described, a main metal plate formed in sections securely fastened together, a crown plate also formed in sections and secured to said main plate at its upper edge, rearwardly directed flanges formed on said main plate and said crown plate and providing a continuous flange around the sides and upper edge of the device, said main plate being provided with a central opening for the terminal of a culvert.

2. In a device of the character described, a main metal plate provided with a central opening adapted to receive the terminal of a culvert, a crown plate secured to the main plate along its upper edge, contiguous rearwardly directed flanges on each of said plates, clips secured to said main plate adjacent its opening for attachment to a culvert, supporting posts secured to the face of said main plate, and additional means for anchoring said plate to the ground.

In testimony whereof I affix my signature.

WALTER E. HITCHCOCK.
